DRILL STEEL GUIDE

Charles F. Osgood, Claremont, N. H., assignor to
 Sullivan Machinery Company, a corporation of
 Massachusetts

Application December 30, 1942, Serial No. 470,565

22 Claims. (Cl. 255—51)

This invention relates to rock drills and more particularly to an improved guide for the drill steel of a rock drill of the mounted type.

In rock drills of the mounted type, the hammer motor which percussively actuates the drill steel is usually mounted on an elongated guiding support suitably positioned in adjacency to the working face, and motor operated feeding means is usually provided for moving the hammer motor back and forth along the guiding support. There is usually provided at the forward end of the guiding support a guide device for centering and guiding the drill steel during starting or "spotting" of a hole in the face, and such guide devices are frequently automatically released from the drill steel as the hammer motor approaches the guide device during forward feed so that accidental contact of the hammer motor with the guide device is prohibited, and permitting movement of the forward end of the hammer motor forwardly past the guide device. Also under certain circumstances, as for instance, subsequently to the starting of a hole with a short drill steel, it is also desirable to effect automatic release of the guide device from the drill steel as the hammer motor is fed rearwardly along the guiding support, thereby to prevent jamming of the drill bit against the guide device, and permitting movement of the drill bit rearwardly past the guide device. It is accordingly desirable to provide a guide device for a drill steel of a mounted rock drill, which is automatically released from the drill steel when the hammer motor assumes a predetermined position on its guiding support during either forward feed or retraction along the support guideways to prohibit unintentional contact of the hammer motor and drill bit with the guide device while the latter is held closed, and possible damage to the drill.

It is accordingly an object of the present invention to provide an improved drill steel guide which is automatically released from the drill steel when the hammer motor assumes a predetermined position along the guideways of its guiding support irrespective of the direction of movement of the hammer motor along the support guideways. Another object is to provide an improved drill steel guide which is automatically released from the drill steel as the hammer motor is fed in either of opposite directions along its guiding support. A further object is to provide an improved drill steel guide which is automatically released from the drill steel either by direct engagement of the hammer motor therewith as the hammer motor is fed forwardly along its

guiding support or by direct engagement of the drill bit therewith as the hammer motor is fed rearwardly along the guiding support. Yet another object is to provide an improved drill steel guide having improved mounting means for the guiding elements thereof and improved means for locking the guiding elements in steel guiding position. A still further object is to provide an improved drill steel guide having the guiding elements thereof mounted for bodily movement in either of opposite directions from a centrally located guiding position, and having improved means for locking the guiding elements in the centrally located guiding position. A further object is to provide an improved drill steel guide of the pivoted arm type having an improved mounting for the guide arms and improved means for locking the guide arms in steel guiding position. Other objects and advantages of the invention will, however, hereinafter more fully appear in the course of the ensuing description and as more particularly pointed out in the appended claims.

In the accompanying drawings there are shown for purposes of illustration two forms which the invention may assume in practice.

In these drawings:

Fig. 1 is a fragmentary side elevational view of a rock drill with which an illustrative embodiment of the invention is associated.

Fig. 2 is a cross sectional view taken substantially on line 2—2 of Fig. 1, showing the drill steel guide in end elevation.

Fig. 3 is a cross sectional view taken substantially on line 3—3 of Fig. 1, showing the guide in steel guiding position.

Fig. 4 is a cross sectional view taken substantially on line 4—4 of Fig. 1, showing the guide in its wide-open, non-guiding position.

Fig. 5 is a horizontal sectional view taken substantially on line 5—5 of Fig. 1.

Fig. 6 is a view in longitudinal vertical section taken substantially on line 6—6 of Fig. 2.

Fig. 7 is a perspective view of the guide arm lock and arm stop.

Fig. 8 is a view similar to Fig. 1, showing another illustrative embodiment of the invention.

Fig. 9 is a cross sectional view taken substantially on line 9—9 of Fig. 8 showing the guide in end elevation.

Fig. 10 is a cross sectional view taken substantially on line 10—10 of Fig. 8, showing the guide in steel guiding position.

Fig. 11 is a cross sectional view taken substan-

tially on line 11—11 of Fig. 8, showing the guide in its wide-open, non-guiding position.

Fig. 12 is a horizontal sectional view taken substantially on line 12—12 of Fig. 8.

Fig. 13 is a perspective view of the latch bar and arm lock shown in Fig. 8.

In both illustrative embodiments of the invention, the improved drill steel guide is shown associated with a conventional hammer rock drill of the mounted drifter type. It will be evident however, that the improved drill steel guide may be associated with rock drills of other types, such as a wagon or tower drill.

The rock drill disclosed herein comprises a conventional hammer motor 4 mounted for movement back and forth along the guideways 2, 2 of a conventional guide shell 3. The hammer motor is of a well known pressure fluid operated type having a motor cylinder 4 provided with lateral guides 5, 5 received in the shell guideways. The motor cylinder contains a usual reciprocating hammer piston for percussively actuating a drill steel 6 suitably mounted in a front chuck housing 7 suitably attached to the front end of the motor cylinder. The drill steel carries a usual detachable drill bit 8 having a rearwardly facing shoulder 9 of larger diameter than the steel body. The hammer motor may be fed along the shell guideways in any conventional manner, either manually or by power, and in this instance, a conventional motor driven feed screw 10, journaled on the guide shell, is employed to feed the hammer motor. Since, as above stated, the rock drill is of a conventional design and is well known to those skilled in the art, further disclosure thereof is herein unnecessary.

Now referring to the embodiment of the invention shown in Figs. 1 to 7 inclusive, it will be observed that attached as by bolts 12, herein three in number, to the forward end of the guide shell 3 are parallel front and rear transverse end-plates 13 and 14 held in proper spaced relation by spacing sleeves 15 and 16 surrounding the bolts between the plates. Formed integral with the rear end-plate 14 is a centrally located bearing boss 17 in which a front bearing portion 18 of the feed screw 10 is journaled as shown in Fig. 6. Pivotally and slidably mounted on the spacing sleeves 15, 15 of the upper pair of bolts intermediate the plates, is a pair of cooperating guide arms 19, 19 each having an appropriately shaped guiding portion 20 for engaging the drill steel. These guide arms are provided with bearing hubs 21 pivotally mounted on the upper spacing sleeves and swingable about their pivotal mountings into and out of steel guiding position. The steel guiding portions 20 of the guide arms, when the latter are in their closed position as shown in Fig. 3, embrace the body of the drill steel to hold the latter centered during starting or "spotting" of a drill hole in the manner well known to those skilled in the art. The wide-open, non-guiding position of the arms is shown in Fig. 4 and, in this position, the arms are swung laterally outside the shell guideways so that the chuck housing may move forwardly between the arms.

In this illustrative construction, the bearing hubs 21 of the guide arms are mounted on the upper pair of spacing sleeves 15, 15 for bodily sliding movement back and forth in a longitudinal direction from a centrally located position. At least in part encircling the upper spacing sleeves 15, 15 at the opposite sides of the arm bearing hubs are coil springs 22 and 23 which constantly urge the guide arms into their centrally located

position substantially midway longitudinally between the end-plates 13 and 14. The coil spring 23 at the forward sides of the guide arms is of the combined compression and torsion type and has coil portions 24 coaxial with the arm pivots and a transverse connecting portion 25 (see Fig. 4) extending between and connecting the coil portions. The ends of the spring engage at 26 the guide arms. Thus, it is evident that the front spring 23 reacts directly between the arms and constantly tends to swing the arms toward their wide-open, non-guiding position. When the guide arms are centrally located longitudinally between the end-plates, they are held in guiding relation with the drill steel by lugs 27 projecting from the arm bearing hubs 21 and engaging the opposite vertical side surfaces 28 of a centrally located locking and stop member 29 herein preferably formed integral with the lower spacing sleeve 16. This lower spacing sleeve 16 is formed at its ends with toothlike projections 30 which are rigidly interlocked with the end plates so that the locking and stop member 29 is held against rotation. When the guide arms are moved bodily longitudinally along the upper spacing sleeves either forwardly or rearwardly, the locking lugs 27 are released from the vertical sides of the member 29, and, at that time, the torsion spring acts automatically to swing the arms wide apart. The locking and stop member 29 is cut away at 31 near its ends to provide clearance for the locking lugs to permit the latter to swing freely past the locking member as the arms swing apart. The arm hubs have spaced projections 32 for engaging the sides of the locking and stop member 29 to limit outward swinging movement of the arms. As shown, the guiding portions 20 of the arms have front and rear projecting bosses 33 and 34 with which the drill bit and chuck housing are adapted directly to engage to move the guide arms bodily either forwardly or rearwardly out of their centrally located, locked position. When the guide arms are in either their forward or rearward position and are unlocked from the locking member 29, the torsion spring 23 quickly swings the arms apart.

The mode of operation of the embodiment above described will be clearly apparent from the description given. When the rock drill is suitably positioned with respect to the working face and it is desired to start or "spot" a drill hole, the guide arms 19, 19, when out of their centrally located position, may be manually swung about their pivots into guiding relation with the drill steel as shown in Figs. 2 and 3, and the arms may then be shoved bodily longitudinally along the upper spacing sleeves 15, 15 into the centrally located position shown in Fig. 1, with the locking projections 27 on the arms abutting the vertical sides 28 of the locking and stop member 29. The coil springs 22 and 23 serve to hold the arms in this centrally located position and the torsion spring 23 holds the lugs tightly against the sides of the locking member. As the hammer motor is fed forwardly along the guideways of the guide shell to feed the drill bit 8 toward the work, the forward end of the chuck housing 7 engages the rear arm bosses 34 to shift the guide arms bodily forwardly along the upper spacing sleeves 15, 15, thereby to release the locking lugs 27 from the vertical sides 28 of the locking member 29. The torsion spring then acts quickly to swing the guide arms apart into their wide-open, non-guiding position shown in Fig. 4, so that, upon continued forward movement of the hammer

motor, the chuck housing may move between the guide arms forwardly past the guide. When the drill hole is started or "spotted" with a short drill steel and for instance, in a wagon or tower drill, it is also desirable to have the guide open automatically as the drill bit is retracted from the work, and during rearward movement of the hammer motor along the shell guideways, the rearwardly facing shoulder 9 on the drill bit 8 engages the front bosses 33 on the guide arms to move the latter bodily rearwardly along the upper spacing sleeves 15, 15 to release the locking lugs 27 from locking engagement with the locking member 29. When the guide arms are unlocked, the torsion spring 23 acts quickly to swing the arms wide apart so that upon continued rearward movement of the hammer motor, the drill bit may move rearwardly past the guide between the guide arms. It is accordingly evident that irrespective of the direction of movement of the hammer motor along the shell guideways, the guide arms are automatically released from the drill steel, thereby to prevent accidental contact of the chuck housing or the drill bit with the guide arms while the latter are held closed, which might result in damage to the drill.

In the embodiment of the invention shown in Figs. 8 to 13 inclusive a pair of front and rear transverse end-plates 36 and 37 are attached as by bolts 38, herein three in number, to the forward end of the guide shell 3 and the plates are maintained in proper spaced relation by spacing sleeves 39 surrounding the bolts between the plates. Pivotally mounted on the pair of upper sleeves 39 is a pair of cooperating guide arms 40, 40 having appropriately shaped portions 41 for engaging the drill steel. In this instance, the guide arms have no bodily sliding movement and are confined solely to swinging movement in transverse planes. The guide arms have bearing hubs 42 which are held against the rear plate 37 by a spring 43 having coils surrounding the upper spacing sleeves between the bearing hubs and the front plate 36. The spring coils are connected by a cross portion 44 and have their ends engaging at 45 the guide arms. This spring is of the combined compression and torsion type and serves not only to swing the guide arms apart, but also yieldingly to hold the guide arms rearwardly against the rear end-plate. This torsion spring constantly urges the guide arms toward their wide-open, non-guiding position shown in Fig. 11, and projections 46 on the arm hubs engage the lower sides of the bearing boss 17 to limit outward swinging movement of the arms.

The guiding portions 41 of one of the guide arms is formed with lateral projections 47 providing a longitudinal guideway 48 which receives a longitudinal shiftable latch bar or lock 49. When the guide arms are swung together into their steel guiding position shown in Fig. 10, a lug 50 on the latch bar may be moved into engagement with a projection 51 on the other guide arm rigidly to lock the arms together. The latch bar has downwardly bent end portions 52, 52 which extend into adjacency to the steel body in the manner shown so that the latch bar may be shifted longitudinally either forwardly or rearwardly by direct engagement of the chuck housing or the drill bit therewith. A spring-pressed plunger 53 on the guide arm which carries the latch bar, engages a suitable detent 54 on the bar yieldingly to hold the latter centrally in its locking position.

The mode of operation of this modified embodiment is as follows: As the hammer motor is fed forwardly along the shell guideways during feed of the drill bit toward the work, the front end of the chuck housing 7 engages the rearwardly bent portion 52 of the latch bar 49 and slides the latch bar forwardly to release the locking lug 50 from the lug 51, thereby to unlock the arms. When the guide arms are unlocked, the torsion spring acts quickly to swing the arms about their pivots into the wide-open, non-guiding position shown in Fig. 11 so that, as forward feed of the hammer motor continues, the chuck housing may move forwardly between the guide arms beyond the guide. As the hammer motor is fed rearwardly along the shell guideways during retraction of the drill bit from the work, subsequently to the "spotting" of a hole with a relatively short starting steel, the rearwardly facing shoulder 9 on the drill bit 8 directly engages the forward bent portion 52 of the latch bar 49 to shift the latter rearwardly to release the locking lug 50 from the locking lug 51. When the guide arms are unlocked, the torsion spring acts quickly to swing the arms wide apart so that upon continued rearward movement of the hammer motor the drill bit may move rearwardly between the guide arms past the guide.

As a result of this invention, it will be noted that an improved drill steel guide is provided which is automatically released from guiding relation with the drill steel when the hammer motor assumes a predetermined position on its guiding support during either forward or reverse movement thereof along the support guideways. It will further be evident that by mounting the guide arms so that they may move bodily either forwardly or rearwardly from a centrally located, locked position, the guide arms may be automatically released from the drill steel by direct engagement of the chuck housing or the drill bit with the guide arms. It will further be evident that by the provision of the improved manner of mounting and arrangement of the guide arms, the latter are automatically moved into their released non-guiding position during feed of the drilling motor in either of opposite directions, in an extremely effective manner. Further by effecting release of the guide arms by direct engagement of the hammer motor or drill bit therewith, all complicated release and actuating devices are eliminated. Other uses and advantages of the improved drill steel guide will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a drill steel guide, a support, a steel guiding element mounted on said support and movable relative thereto into and out of steel guiding position, said guiding element also being movable bodily forwardly and rearwardly longitudinally, relative to said support, means for yieldingly holding said guiding element in a centrally located position longitudinally of said support, means for locking said guiding element in steel guiding position when in said centrally located position, said locking means being re-

leasable upon bodily movement of said guiding element either forwardly or rearwardly from said centrally located position relative to said support, and means for automatically moving said guiding element out of steel guiding position when said locking means is released.

2. In a rock drill, a support providing a longitudinal guideway, a drill steel actuator movable longitudinally along said support guideway and adapted to actuate a drill steel carrying a drill bit, and a drill steel guide mounted on said support and including a guiding element movable into and out of steel guiding position, means for locking said guiding element in steel guiding position, said locking means being releasable either by direct engagement of said actuator with said guiding element or of said drill bit with said guiding element, and means operable independently of movement of said actuator or said bit with respect to said support for automatically moving said guiding element into non-guiding position out of the path of movement of said actuator or said bit when said locking means is released.

3. In a rock drill, a support providing a longitudinal guideway, a drill steel actuator movable longitudinally along said support guideway and adapted to actuate a drill steel carrying a drill bit, and a drill steel guide mounted on said support and including a guiding element movable into and out of steel guiding position, means for locking said guiding element in steel guiding position and including a reciprocable lock release element movable longitudinally of said support, and having a portion engageable directly by said actuator as the latter moves forwardly along said support guideway and another portion engageable directly by said drill bit as said actuator moves rearwardly along said support guideway, said lock release element effecting release of said locking means upon either direction of movement thereof, and means for automatically moving said guiding element into non-guiding position when said locking means is released.

4. In a rock drill, a support providing a longitudinal guideway, a drill steel actuator movable forwardly and rearwardly along said support guideway and adapted to actuate a drill bit, and a drill steel guide mounted on said support and including a guiding element movable into and out of steel guiding position, said guiding element being movable bodily forwardly and rearwardly from a centrally located position longitudinally relative to said support, means for locking said guiding element when in its centrally located position in guiding relation with the drill steel, said locking means being releasable either by direct engagement of said steel actuator with said guiding element as said actuator moves forwardly along said guideway or by direct engagement of the drill bit with said guiding element during rearward movement of said actuator along said guideway, and means for moving said guiding element out of guiding relation with the drill steel when said locking means is released.

5. In a rock drill, a support providing a longitudinal guideway, a drill steel actuator movable forwardly and rearwardly along said support guideway and adapted to actuate a drill steel carrying a drill bit, and a drill steel guide mounted on said support and including a guiding element movable into and out of steel guiding position, said guiding element being movable bodily forwardly and rearwardly from a centrally

located position longitudinally relative to said support, means for yieldingly holding said guiding element in its centrally located position, means for locking said guiding element when in its centrally located position in guiding relation with the drill steel, said locking means being releasable either by direct engagement of said steel actuator with said guiding element as said actuator moves forwardly along said guideway or by direct engagement of the drill bit with said guiding element during rearward movement of said actuator along said guideway, and means for moving said guiding element out of guiding relation with the drill steel when said locking means is released.

6. In a drill steel guide, a support, a guiding element mounted on said support and movable relative thereto into and out of steel guiding position, said guiding element also being movable either forwardly or rearwardly from a centrally located position bodily longitudinally relative to said support, and means for locking said guiding element in steel guiding position when the same is in its centrally located position on said support, said locking means being releasable upon bodily movement of said guiding element in either direction longitudinally relative to said support.

7. In a drill steel guide, a support, a guiding element mounted on said support and movable relative thereto into and out of steel guiding position, said guiding element also being movable either forwardly or rearwardly from a centrally located position bodily longitudinally relative to said support, and yieldingly holding said guiding element in said centrally located position, and means for locking said guiding element in steel guiding position when the same is in its centrally located position on said support, said locking means being releasable upon bodily movement of said guiding element in either direction longitudinally of said support.

8. In a drill steel guide, a support, a guiding element mounted on said support and movable relative thereto into and out of steel guiding position, said guiding element also being movable either forwardly or rearwardly from a centrally located position bodily longitudinally relative to said support, and means for locking said guiding element in steel guiding position when the same is in its centrally located position on said support, said locking means being releasable upon bodily movement of said guiding element in either direction longitudinally of said support, and means for automatically moving said guiding element out of its steel guiding position when said locking means is released.

9. In a drill steel guide, a support, a steel guiding element mounted on said support and movable relative thereto into and out of steel guiding position, and means for locking said guiding element in its steel guiding position movable longitudinally either forwardly or rearwardly relative to said support into released position.

10. In a drill steel guide, a support, a guiding element mounted on said support and movable relative thereto into and out of steel guiding position, and means for locking said guiding element in its steel guiding position including a shiftable lock releasing element mounted on said guiding means and movable longitudinally either forwardly or rearwardly relative to said support into lock releasing position.

11. In a drill steel guide, a support, a steel guiding means mounted on said support and

movable into and out of steel guiding position, said guiding means being movable bodily longitudinally relative to said support either forwardly or rearwardly from a centrally located position, and means for locking said guiding means in steel guiding position when the same is in said centrally located position, said locking means being releasable upon bodily movement of said guiding means in either direction from said centrally located position.

12. In a drill steel guide, a support, a steel guiding means mounted on said support and movable into and out of steel guiding position, said guiding means being movable bodily longitudinally relative to said support either forwardly or rearwardly from a centrally located position, means for yieldingly holding said guiding means in its centrally located position, and means for locking said guiding means in steel guiding position when the same is in said centrally located position, said locking means being releasable upon bodily movement of said guiding means in either direction from said centrally located position.

13. In a rock drill, a support providing a longitudinal guideway, a drill steel actuator movable longitudinally either forwardly or rearwardly along said support guideway and adapted to actuate a drill steel carrying a drill bit, and a drill steel guide mounted on said support and including steel guiding means movable into and out of steel guiding position, and means for locking said guiding means in steel guiding position, said locking means being releasable either by direct engagement of said guiding means by said steel actuator as the latter moves forwardly along said support guideway or by direct engagement of said guiding means by the drill bit as said actuator moves rearwardly along said support guideway, said guiding means being movable upon release of said locking means out of the path of movement of said actuator or said bit.

14. In a rock drill, a support providing a longitudinal guideway, a drill steel actuator movable longitudinally either forwardly or rearwardly along said support guideway and adapted to actuate a drill steel carrying a drill bit, and a drill steel guide mounted on said support including steel guiding means movable into and out of steel guiding position, said guiding means also being movable bodily either forwardly or rearwardly from a centrally located position longitudinally relative to said support, and means for locking said guiding means in steel guiding position when the same is centrally located and releasable upon bodily movement of said guiding means in either direction, said locking means being releasable either by direct engagement of said guiding means by said steel actuator as the latter moves forwardly along said support guideway or by direct engagement of said guiding means by the drill bit as said actuator moves rearwardly along said support guideway.

15. In a rock drill, a support providing a longitudinal guideway, a drill steel actuator movable longitudinally either forwardly or rearwardly along said support guideway and adapted to actuate a drill steel carrying a drill bit, and a drill steel guide mounted on said support including steel guiding means movable into and out of steel guiding position, and means for locking said guiding means in steel guiding position including a lock releasing element movable bodily either forwardly or rearwardly from a centrally located position longitudinally relative to said support, said locking means being releasable either by di-

rect engagement with said releasing element by said steel actuator as the latter moves forwardly along said support guideway or by direct engagement with said releasing element by the drill bit as said steel actuator moves rearwardly along said support guideway.

16. In a drill steel guide, a support, steel guiding means mounted on said support and movable bodily either forwardly or rearwardly from a centrally located steel guiding position longitudinally relative to said support, and means for locking said guiding means in guiding relation with the drill steel when in said centrally located steel guiding position, said locking means being releasable upon bodily movement of said guiding means in either direction.

17. In a rock drill, a support providing a longitudinal guideway, a drill steel actuator for actuating the drill steel carrying a drill bit and movable back and forth along said support guideway, a drill steel guide mounted on said support, and means for locking said guide in its steel guiding position releasable automatically either by direct engagement of the steel actuator with said guide as said steel actuator moves forwardly along side guideway or by direct engagement with said guide by the drill bit as said steel actuator moves rearwardly along said guideway.

18. In a drill steel guide, a support, a drill steel guiding means mounted on said support and movable bodily either forwardly or rearwardly longitudinally relative thereto from a centrally located position, and means operative when said guiding means is in said centrally located position for holding said guiding means in guiding relation with a drill steel, said holding means being releasable automatically to free said guiding means from steel engagement upon movement of said guiding means either forwardly or rearwardly from said centrally located position.

19. In a drill steel guide, a pair of cooperating steel guiding elements mounted for bodily movement in opposite directions, and means for locking said guiding elements in guiding relation with a drill steel including a stationary locking member, and locking projections on said guiding elements engaging said locking member, said locking projections being releasable from said locking member to free said guiding elements from guiding relation with the drill steel upon bodily movement of said guiding elements in either direction.

20. In a drill steel guide, a pair of cooperating steel guiding elements, and means for locking said elements in guiding relation with a drill steel including a reciprocable latch mounted on one guiding element and engageable with a locking projection on said other guiding element, and releasable to free said guiding elements for movement out of steel guiding relation upon movement of said latch in either of opposite directions from a centrally located locking position.

21. In a rock drill, a support providing a longitudinal guideway, a drill steel actuator movable longitudinally along said support guideway and adapted to actuate a drill steel carrying a drill bit, a drill steel guide mounted on said support and including a guiding element movable into and out of steel guiding position about an axis parallel to the drill steel axis, means for locking said guiding element in steel guiding position including a locking member coacting with said element, said guiding element being locked in steel guiding position when said locking member and said guiding element are in a predeter-

mined relative position and being releasable by relative movement between the same and said locking member in either of opposite directions from such position, and means for automatically moving said guiding element into non-guiding position when said locking means is released.

22. In a rock drill, a support providing a longitudinal guideway, a drill steel actuator movable longitudinally along said support guideway and adapted to actuate a drill steel carrying a drill bit, a drill steel guide mounted on said support and including a guiding member movable into and out of steel guiding position, means for locking said guiding member in steel guiding position including a locking member coacting

5 with said guiding member, said guiding member being positively locked against movement away from the steel when said locking member and said guiding member are in a predetermined relative position from which one of them is movable in either of opposite directions to effect release of said guiding member, said one member having oppositely facing surfaces respectively engageable by said actuator and by said bit for moving the 10 same in said opposite directions, and means for automatically moving said guiding member into non-guiding position as soon as the same is released.

CHARLES F. OSGOOD.
